SUCTION PUMP

Henry de Forrest, 3604 Sunswep Drive,
Studio City, Calif.

Filed Aug. 27, 1963, Ser. No. 76,371

Term of patent 14 years

(Cl. D65—1)

FIG. 1 is a perspective view of a suction pump showing my new design.

FIG. 2 is a front elevational view of the suction pump shown in FIG. 1.

FIG. 3 is a plan view of the suction pump shown in FIG. 1.

FIG. 4 is a side elevational view of the suction pump shown in FIG. 1.

The dominant features of my new design reside in the portions shown in the drawing in full lines. The inlet tube has been shown broken away to indicate indeterminate length.

I claim:

The ornamental design for a suction pump, substantially as shown and described.
